UNITED STATES PATENT OFFICE

90,659

DESIGN FOR A COMBINED JACK AND BUMPER

Albert C. Hoecker, St. Louis, Mo.

Application April 30, 1932. Serial No. 43,664

Term of patent 7 years

To all whom it may concern:

Be it known that I, ALBERT C. HOECKER, a citizen of the United States, residing at St. Louis, in the State of Missouri, have invented a new, original, and ornamental Design for a Combined Jack and Bumper, of which the following is a specification, reference being had to the accompanying drawing, forming part thereof.

Figure 1 is a front view of the device; and Figure 2 is a top plan view of the same.

I claim:

The ornamental design for a combined jack and bumper, as shown.

ALBERT C. HOECKER.
